UNITED STATES PATENT OFFICE.

JOHN LEVEY, OF CHICAGO, ILLINOIS.

COMPRESSOR.

977,662.

Specification of Letters Patent. Patented Dec. 6, 1910.

Application filed April 14, 1910. Serial No. 555,367.

To all whom it may concern:

Be it known that I, JOHN LEVEY, a citizen of the United States, residing at Chicago, in the county of Cook and State of Illinois, have invented a new and useful Improvement in Compressors, of which the following is a specification.

My invention relates to improvement in compressors for compressing air or gas; and my objects are, generally stated, to provide a simple and compact form of compressor which shall be economical of manufacture and by which relatively high compression of the air or gas operated on may be effected.

Referring to the accompanying drawings—Figure 1 is a view in elevation of a compressor constructed in accordance with my invention, the compressor-proper being shown in longitudinal sectional elevation, the section being taken at the line 1 on Fig. 3. Fig. 2 is a transverse section, taken through the compressor, the piston of the compressor being shown in one of the positions it assumes while operating. Fig. 3 is a section taken at the line 3 on Fig. 1 and viewed in the direction of the arrow, this view showing the piston in another position and illustrated in elevation. Fig. 4 is a section taken at the line 4 on Fig. 1 and viewed in the direction of the arrow. Fig. 5 is a view in vertical sectional elevation of the rotary piston-cylinder employed; and Fig. 6, a top plan view of the cylinder of Fig. 5 with portions thereof broken away to disclose a detail.

The base of the compressor, represented at 10 supports the casing 11 of the compressor-proper which is formed of a central cylindrical section 12 and end-sections 13 centrally apertured as represented at 14 and 15, the section 12 being secured between the sections 13 as by bolts 16. The section 12 contains a series of communicating chambers 17 forming a water-jacket for this section through which water supplied through the pipe 18 and discharged through the pipe 19, circulates. The section 12 contains a centrally-disposed opening 20 of cylindrical shape, the wall of which is represented at 21, this wall which forms with the inner walls of the sections 13, a cylindrical chamber 22, being recessed at one side thereof on its inner surface as indicated at 23 into which recess a pipe 24 leading from the source of fluid to be compressed, opens. The section 12 near its upper end, a slight

distance to the right of its vertical center (Fig. 2), contains an opening 25 through it into which the reduced end of a check-valve 26 extends, this valve being secured at its annularly-flanged portion 27 to the section 12, as by bolts 28. The check-valve shown is of a well-known construction, its valve-disk 29 on the stem 30 being downwardly spring-pressed against a seat 31 which contains an opening 32 communicating with the interior of the chamber 22 and with the compressed fluid-outlet 33 through which the compressed fluid is conducted away from the compressor.

Journalized in the bearing 15 is a hollow shaft 34 carrying on its inner end a cylindrical member 35 which is located in the chamber 22 and contains an opening 36, preferably circular in cross-section, through it and extending at right-angles to the axis upon which it rotates as hereinafter described, the opening 36 at its opposite ends portions being annularly recessed as indicated at 37 to form annular shoulders 38. Located in the opposite ends of the opening 36 in the member 35 are bushings 39, the outer ends of which are convexed to cause them to conform to the wall 21 against which they are held in contact as herein-after described, during the rotation of the member 35. These bushings are flanged on their peripheries at their outer ends as represented at 40 to present shoulders 41 which oppose the shoulders 38 as clearly represented in Fig. 1, the inner ends of these bushings being provided on their circumference with packing-rings 42 which bear against the inner surface of the wall of the opening 36. Reciprocably confined in the bushings 39 is a cylindrical piston 43 which is of less length than the diameter of the member 35 and is provided with packing-rings 44 on its outer surface toward its opposite ends, which bear against the inner surface of the bushings 39.

The piston 43 which is preferably hollow, has its ends rounded to conform to the wall 21 of the chamber 22 as illustrated in Fig. 2 and is formed intermediate its ends with a pair of spaced transversely-extending cross-members 45 forming guides in which a block 46 is slidably confined, this block containing an opening 47 forming a bearing for a crank-arm 48 fixed on a non-rotary shaft 49 keyed in the opening 14 and alining with the axis upon which the sleeve 34 rotates,

the crank 48 projecting through an opening 50 in the member 35 and into a recess 51 in the side of the piston. The crank is so arranged as to cause its pin 48 to be positioned directly above the center of the shaft carrying it as illustrated in Figs. 2 and 3, and the parts described are so proportioned as to cause the upper end of the piston 43, when the latter assumes vertical position during its operation as hereinafter described, to be substantially in contact with the wall 21 as represented in Fig. 3.

The member 35 is rotated through the medium of a shaft 52 fixed at one end in the sleeve 34 as by pins 53 and journaled at its opposite end in a bearing 54 supported on the base 10, the shaft in the particular construction illustrated carrying tight and loose pulleys 55 and 56, respectively, which may have belt connection with any suitable power device, though the member 35 may be rotated in any other suitable manner.

The operation of the compressor is as follows: Rotation of the shaft 52 rotates the shaft 34 and consequently the member 35, in the direction indicated by the arrow in Fig. 2, the piston 43 in this operation reciprocating in contact with the inner surfaces of the bushings 39, by reason of its eccentric connection, through the medium of the crank 48, with the shaft 49, for alternately moving the ends of the piston toward the wall 21.

The parts of the construction are so proportioned and arranged that, as the ends of the piston 43 are successively moved to a position in which they oppose the recess 23 in the section 12, they will be withdrawn inwardly into the member 35 to their fullest extent, the fluid to be compressed entering the pockets thus formed between the inner walls of the bushings 39 and the ends of the piston 43; and when moved to a position in which they oppose the outlet 32 will be at the limit of their outward movement, in which they substantially contact with the wall 21 of the chamber 22. Thus, as the member 35 is rotated, the piston 43 reciprocates back and forth therein, and permits the fluid to enter the pockets formed as described when opposed to the recesses 23, in which pockets it is highly compressed by the action of the piston in moving outwardly toward the wall 21 against the body of fluid confined therein. The act of compressing the fluid continues until the pocket containing it opposes the outlet 32, whereupon the fluid in highly compressed condition discharges through this outlet against the disk 29 which opens and permits the fluid to pass through the outlet 28. It will be understood that the fluid will begin to exhaust from the pockets in which it is compressed as soon as the edge of the pocket passes the wall of the openings 32, at which point the

end of the piston in its movement will be spaced a slight distance from the wall 21, the piston moving into substantial engagement with the wall 21 before it passes the opening 32, whereby substantially all of the fluid introduced into the pockets will be forced through the outlet 32. It will furthermore be noted that the ends of the cylinder, in which the piston 43 moves, alternately operate by the action of the piston to receive a charge of fluid for compression by the piston as the latter moves outwardly, and to discharge the same after compression through the outlet 32. To maintain the outer ends of the bushings 39 in sufficiently close contact with the wall 21 to prevent the escape of the fluid from the pockets formed in the member 35 by the action of the piston as described, while the fluid is undergoing compression, I provide coiled springs 57 confined in sockets 58 in the member 35 which bear against the shouldered portions 41 of the bushings 39 and tend to force the ends of these bushings against the wall 21; and to supplement the action of these springs I provide passages 59 in the bushings 39 which open into the interior of the latter and into the joints formed between the shouldered portions 38 and 41 of the member 35 and bushings 39, respectively, through which passages the fluid while undergoing compression is permitted to enter these joints and exert a pressure between the surfaces 38 and 41 sufficient to force the bushings 39 against the wall 21 for preventing the escape of the compressed fluid from the interior of these bushings when moving from receiving to discharging position. Thus, as the pressure of the fluid in the member 35 increases as it is carried toward the outlet 32, the pressure tending to force the bushings outward correspondingly increases, with the result of maintaining the desired frictional engagement of the outer ends of the bushings with the wall 21 for permitting the compression of the fluid to an exceedingly high degree.

As a means for preventing the piston from turning in the bushings, I provide in the inner end of the shaft 34 an inwardly-projecting circular ended block 60 which extends into engagement with the parallel walls 61 of a longitudinally-extending recess 62 in the adjacent side of the piston 43.

It will be manifest that a compressor constructed in accordance with my invention is capable of not only exerting the desired force for compressing the fluid to a high degree, but serves to effectually imprison the fluid so compressed until it has been carried to the position for discharge.

While I have described the action of the gas undergoing compression against the bushings for forcing them outwardly as supplemental to that of the springs, I do not

wish to be understood as intending to limit my invention to the employment of mechanical means for forcing the bushings outwardly in connection with the action of the gas against said bushings, as such mechanical means may be dispensed with and the gas alone force the bushings with such pressure against the wall 21 as to insure the desired compression.

10. What I claim as new, and desire to secure by Letters Patent, is--

1. A compressor comprising, in combination, a casing containing a chamber having a cylindrical wall provided with an inlet for the fluid to be compressed and with an outlet for the compressed fluid, a rotary piston-cylinder in said chamber provided at its ends with ring-shaped members surrounding the opening through said cylinder and convexed at their outer ends and adapted to bear against said cylindrical wall, means for forcing said ring-shaped members into engagement with said cylindrical wall, a piston reciprocably confined in said cylinder, and means operating to reciprocate said piston during the rotation of said cylinder for compressing fluid introduced into the cylinder through said inlet.

2. A compressor comprising, in combination, a casing containing a chamber having a cylindrical wall provided with an inlet for the fluid to be compressed and an outlet for the compressed fluid, a rotary piston-cylinder in said chamber the inner surface of which toward its opposite ends is lined with separate bushings having their outer ends convexed and movably supported in said cylinder, means for forcing said bushings into engagement with the inner wall of said chamber, a piston reciprocably confined in said cylinder, and means operating to reciprocate said piston during the rotation of said cylinder for compressing fluid introduced into the cylinder through said inlet.

45. 3. A compressor comprising, in combination, a casing containing a chamber having a cylindrical wall provided with an inlet for the fluid to be compressed and with an outlet for the compressed fluid, a rotary piston-cylinder in said chamber the inner surface of which toward its opposite ends is recessed to afford shoulders and is lined with separate movable bushings having their outer ends convexed and provided with shouldered portions on their peripheries overlapping the shoulders on said cylinder, means operating against the shouldered portions of said rings for forcing the latter into engagement at their ends with the wall of said chamber, a piston reciprocably confined in said cylinder, and means operating to reciprocate said piston during the rotation of said cylinder for compressing fluid introduced into the cylinder through said inlet.

65. 4. A compressor comprising, in combina-

tion, a casing containing a chamber having a cylindrical wall provided with an inlet for the fluid to be compressed and with an outlet for the compressed fluid, a rotary piston-cylinder in said chamber, the inner surface of which is lined with separate movable bushings having their outer ends convexed and presenting surfaces extending at an angle to the path through which the piston reciprocates, means operating against said angularly-disposed surface for forcing the bushings into engagement with the cylindrical wall of said chamber, a piston reciprocably confined in said cylinder, and means operating to reciprocate said piston during the rotation of said cylinder for compressing fluid introduced into the cylinder through said inlet.

5. A compressor comprising, in combination, a casing containing a chamber having a cylindrical wall provided with an inlet for the fluid to be compressed and with an outlet for the compressed fluid, a rotary piston-cylinder in said chamber provided at its ends with ring-shaped members surrounding the opening through said cylinder and convexed at their outer ends and adapted to bear against said cylindrical wall, a piston reciprocably confined in said cylinder, and means operating to reciprocate said piston during the rotation of said cylinder for compressing fluid introduced into the cylinder through said inlet, said ring-shaped members being adapted to be acted upon by the fluid as it is undergoing compression, for forcing said members at their outer ends against said cylindrical wall.

6. A compressor comprising, in combination, a casing containing a chamber having a cylindrical wall provided with an inlet for the fluid to be compressed and with an outlet for the compressed fluid, a rotary piston-cylinder in said chamber, a piston reciprocably confined in said cylinder, means operating to reciprocate said piston during the rotation of said cylinder for compressing fluid introduced into the cylinder through said inlet, and ring-shaped members provided on said cylinder and having their ends convexed and provided with surfaces extending at an angle to the path through which the piston reciprocates adapted to be acted on by the fluid as it is undergoing compression for forcing said members at their outer ends against said cylindrical wall.

7. A compressor comprising, in combination, a casing containing a chamber having a cylindrical wall provided with an inlet for the fluid to be compressed and with an outlet for the compressed fluid, a rotary piston-cylinder in said chamber, a piston reciprocably confined in said cylinder, means operating to reciprocate said piston during the rotation of said cylinder for compressing fluid introduced into the cylinder through

said inlet, and bushings lining the inner surface of said cylinder having their outer ends convexed and presenting surfaces extending at an angle to the path through which the piston reciprocates, said bushings containing passages for permitting the fluid while undergoing compression to act against their angularly-disposed surfaces for forcing them against said cylindrical wall.

10 8. A compressor comprising, in combination, a casing containing a chamber having a cylindrical wall provided with an inlet for the fluid to be compressed and an outlet for the compressed fluid, a rotary piston-cylinder in said chamber, the inner surface of which toward its opposite ends is recessed outwardly to afford shoulders and is lined

with separate movable bushings having their outer ends convexed and provided with shouldered portions on their peripheries 20 overlying the shoulders on said cylinder, said bushings containing passages opening into the interior of the bushings and into the joints between said opposing shouldered portions, a piston reciprocably confined in 25 said cylinder, and means operating to reciprocate said piston during the rotation of said cylinder for compressing fluid introduced into the cylinder through said inlet.

JOHN LEVEY.

In presence of—

R. A. SCHAEFER,
JOHN WILSON.
